US00D929881S

(12) **United States Design Patent** (10) Patent No.: **US D929,881 S**
(45) Date of Patent: ** Sep. 7, 2021

(54) **SPECTROPHOTOMETER**

(71) Applicant: **Agilent Technologies, Inc.**, Santa Clara, CA (US)

(72) Inventors: **Dale Hathaway**, Oxford (GB); **Daniela Loraing**, Waldbonn (DE); **Maximilian Schneider**, Waldbonn (DE); **Craig Peters**, Mulgrave (AU); **Stuart Bonthron**, Oxford (GB); **Scott Harwood**, Oxford (GB)

(73) Assignee: **Agilent Technologies, Inc.**, Santa Clara, CA (US)

(**) Term: **15 Years**

(21) Appl. No.: **29/696,775**

(22) Filed: **Jul. 1, 2019**

(51) LOC (13) Cl. **10-04**

(52) U.S. Cl.

USPC **D10/81**

(57) **CLAIM**

The ornamental design for a spectrophotometer, as shown and described.

DESCRIPTION

FIG. 1 is front, right, top perspective view of a spectrophotometer showing our new design;

FIG. 2 is a back, left, bottom perspective view thereof;

FIG. 3 is a front elevational view thereof;

FIG. 4 is a right elevational view thereof;

FIG. 5 is a back elevational view thereof;

FIG. 6 is a left elevational view thereof;

FIG. 7 is a top plan view thereof; and,

FIG. 8 is a bottom plan view thereof.

The broken lines showing the screen and clasps form no part of the claimed design.

1 Claim, 5 Drawing Sheets
